Isaac A. Sheppard and Curtis Holzer of Philadelphia Penna.
Letters Patent No 2098 Dated June 18-1865
Design for cook's stove.

The schedule referred to in these Letters Patent and making part of the same.

To all whom it may concern:

Be it known that we, Isaac Sheppard and J. Holzer, both of Philadelphia, County of Philadelphia, State of Pennsylvania, have invented and produced a new and original design for the plates of a cook stove, and we do hereby declare the accompanying drawing with the following explanation of the same to form a full, clear and exact description of the said design.

Fig. 1 of the drawing represents a front plate of the stove.

Fig. 2, the side plate, and

Fig. 3, the back plate.

To the front plate A are hung the doors B. B. and above the latter is the register C, which slides in an oblong panel enclosed by a moulding a.

Near the edges of the plate A is a heading b, and on the face of the plate at each side of the same is a shield c, from the top and bottom of which extend radial serrated projections d, and diagonally across the shield extends a belt.

Round the edges of each of the doors B is a plain heading e, and in the centre of each door is a shield from which extend radial serrated projections d.

To the side plates D are hung the doors F G. H, each of which is bordered by a plain heading e, and has in the centre an ornamental design similar to that in the doors B of the front plate.

On the belt which extends across the shield on the door F is the word "Monumental," and on the face of the plate, above the door F is a scroll I.

2 DES. 2098

A plain beading b, similar to the beading b, on the front plate, extends round the edge of the side plate.

Near the edge of the back plate b is a beading b, similar to the beading b, and in the centre of this plate is an ornamental design similar to that in the door b of the side plate.

We claim.

The ornamental figures and forms substantially as shown in and by the accompanying drawing, the whole forming an ornamental design for the plates of a cook stove.

In testimony whereof we have signed our names to this specification in the presence of two subscribing witnesses.
